INFLATABLE ATTACHMENT FOR BRASSIERE

Philip White, Norfolk, Va.

Application February 17, 1956, Serial No. 566,224

3 Claims. (Cl. 128—462)

This invention relates to improvements in inflatable brassieres and is a continuation-in-part of application Serial No. 405,076, now Patent No. 2,741,769, which discloses a one-piece brassiere having a body encircling foundation piece and inflatable bust receiving pockets. The present application relates to an improvement in inflatable brassieres wherein separate inflatable attachments are constructed to fit over the bust receiving pockets of the conventional brassiere and are provided with air sacks, these inflatable attachments being secured to the bust receiving pockets of any conventional brassiere.

Various types of padding, generally of soft resilient latex, have been employed in brassieres to give a desired contour to the bust of the wearer, and for the purpose, brassieres having inflatable pockets have also been employed. The ultimate purpose of such apparel is to improve the appearance of the wearer and consequently, to satisfy this requirement, the apparel must simulate a natural bust form of the desired contour. In the past, devices of the kind above mentioned have failed in some degree by reason of the fact that in establishing the desired bust contour, they, of necessity, had a rigidity which is not characteristic of a natural bust of the same form. The purpose of this invention is to provide an improved inflatable attachment for the conventional brassiere which will give the wearer the desired bust contour and at the same time the natural characteristics of a bust form of the kind being simulated.

In application Serial No. 405,076, (Patent No. 2,741,769), there is provided a brassiere which has inflatable pockets which overlie the breasts of the wearer, and constitute an integral part of the one-piece brassiere. Leading to each of the pockets is an air tube through which the wearer may force and withdraw a supply of air in addition to that which maintains the inflatable pockets in their desired condition of expansion. The additional air supply is forced into and released from the inflatable pockets by means of an air sack communicating with each air tube and which are supported on the brassiere so that they are positioned, respectively, immediately beneath the armpits of the wearer. In this manner, the natural movement of the arms of the wearer, while walking or otherwise moving about, will force into and release from the inflatable pockets of the brassiere the additional quantity of air, and this will impart a natural appearing bust movement to the wearer of the brassiere.

In the present invention an inflatable attachment is added to the bust receiving pockets of the foundation piece. This attachment consists of a pair of inflatable bust receiving pockets, each pocket having an outer and inner layer of elastic air impervious material. The peripheral portions of these pockets are airtight and the pockets are designed to fit over the bust receiving pockets of the foundation piece. Each of the inflatable pockets is attached to an air impervious air sack by means of an air tube. The inflatable pockets and the air sacks are

2

attached to the brassiere by any conventional means such as snaps, clips, etc.

The invention may be better understood by reference to the following detailed description made with reference to the accompanying drawings.

In the drawings:

Figure 1 is a front elevational view of a brassiere to which is secured the separate brassiere attachments; Figure 2 is a vertical sectional view along the line

10 2—2 of Figure 1; and

Figure 3 is a vertical sectional view on the line 3—3 of Figure 1.

Figure 1 illustrates a conventional one piece brassiere to the bust receiving pocket of which has been attached

15 inflatable attachments. The brassiere comprises a foundation piece 20 and bust receiving pockets 21. Over the bust receiving pockets 21 the removable inflatable pockets

22 and 24 are fitted. Inflatable pockets 22 and 24 are constructed of an inner and outer layer of elastic air

20 impervious material shaped to provide a cupped contour normally presenting a convex front surface and an inner

layer of air impervious material providing a concave rear surface. Each of the pockets 22 and 24 fits about the

25 bust receiving portion 21 of the foundation piece 20. The inflatable attachments 22 and 24 are attached to the bust

receiving pockets of the conventional brassiere by means of

20 snaps such as those indicated at 25, stays, clips, etc. An air tube 26 communicates at one end with each of

30 the pockets 22 and 24. The other end of each of these tubes 26 connects with an air sack 28. The sacks 28

35 are likewise removably attachable to the brassiere structure by means of snaps or stays such as indicated generally at 29 in Figure 3. Thus, the sacks 28 may be

35 supported on the brassiere so that they will be positioned beneath the arms of the wearer or may be secured at

another point where they may be easily pumped so that the additional air in these sacks 28 may be forced

up into the removable pockets 22 and 24. The sacks 28

40 are, like the inflatable pockets, constructed of elastic air

impervious material each constituting a closed unit which

45 may be placed at any convenient location. In other words, the sacks may be positioned under the arm as

shown in Figure 1 or, with a longer tube 26, may even be positioned at a point where they are not attached to

the foundation piece of the brassiere.

The embodiment of the invention shown in Figures 1 to 3 is of great value in that it may be attached to any conventional brassiere. In other words, it is not necessary to construct the complete undergarment with

50 inflatable pockets as an intrinsic part thereof. By embodying the attachable inflatable pockets with operatively attached air sacks, it is now possible to attain the same results as would be obtained with the employment of

55 the one-piece inflatable brassiere. Moreover, since this attachment may be used on any conventional brassiere, its employment is not restricted to the one undergarment

specifically constructed with inflatable pockets.

Having thus described my invention, what is claimed as new and desired to be secured by Letters Patent is:

60 1. In combination with a brassiere having a foundation piece of body encircling structure and a pair of bust receiving pockets, an attachment comprising a pair of

65 inflatable pockets removably secured on the foundation piece, each pocket having an outer layer of elastic air impervious material providing a cupped contour

65 normally presenting a convex front surface and an inner layer of air impervious material providing a concave rear surface, said inner layer fitting flush with the

70 bust receiving pockets of said brassiere foundation piece, said layers being joined at their peripheral portions to one another to provide an air retaining space between them, means for attaching said pockets to said founda-

tion piece, a pair of air sacks one on each side of the foundation piece to be adjacent an arm when on the body of the wearer, each sack having an outer and an inner layer of air impervious material to provide an air retaining space and being disposed so that movement of the wearer's body when said brassiere is being worn alternately causes deflation and inflation of said sack, and air tubes connecting said pockets to said air sacks whereby deflation and inflation of said sacks alternately forces air through said air tubes respectively into and out of said bust receiving pockets.

2. In combination with a brassiere having a foundation piece of body encircling structure and a pair of bust receiving pockets removably secured on the foundation piece, an attachment comprising a pair of inflatable pockets, each pocket having an outer layer of elastic air impervious material providing a cupped contour normally presenting a convex front surface and an inner layer of air impervious material providing a concave rear surface, said inner layer fitting flush with the bust receiving pockets of said brassiere foundation piece, said layers being joined at their peripheral portions to one another to provide an air retaining space between them, means for attaching said pockets to said foundation piece, a pair of air sacks one on each side of the foundation piece to be adjacent an arm when on the body of the wearer, each sack having an outer and an inner layer of air impervious material to provide an air retaining space and being disposed so that movement of one arm of the wearer when said brassiere is being worn alternately causes deflation and inflation of said sack, means for attaching said air sacks to said foundation piece, and air tubes connecting said pockets to said air sacks whereby deflation and inflation of said sacks alternately forces air through said air tubes respectively into and out of said bust receiving pockets.

3. In combination with a brassiere having a foundation piece of body encircling structure and a pair of bust receiving pockets, an attachment comprising a pair of inflatable pockets removably secured on the foundation piece, each pocket having an outer layer of elastic air impervious material providing a cupped contour normally presenting a convex front surface and an inner layer of air impervious material providing a concave rear surface, said inner layer fitting flush with the bust receiving pockets of said brassiere foundation piece, said layers being joined at their peripheral portions to one another to provide an air retaining space between them, means for attaching said pockets to said foundation piece, a pair of air sacks one on each side of the foundation piece to be adjacent an arm when on the body of the wearer, each sack having an outer and an inner layer of air impervious material to provide an air retaining space and being disposed on said foundation piece adjacent one upper arm of the wearer, when said brassiere is being worn, so that movement of the upper arm toward and away from the body alternately causes deflation and inflation of said sack, means for attaching said air sacks to said foundation piece, and substantially flat air tubes connecting said pockets to said air sacks whereby deflation and inflation of said sacks alternately forces air through said air tubes respectively into and out of said bust receiving pockets.
